UNITED STATES PATENT OFFICE.

LADBROOK H. FREEMAN, OF CLEVELAND, OHIO, ASSIGNOR TO THE GUGGENHEIM LAUNDRY MACHINERY CO., OF CLEVELAND, OHIO.

IRONING-MACHINE.

1,260,532.

Specification of Letters Patent. Patented Mar. 26, 1918.

Application filed March 26, 1912. Serial No. 886,320.

To all whom it may concern:

Be it known that I, LADBROOK H. FREEMAN, a citizen of the United States, residing at Cleveland, in the county of Cuyahoga and State of Ohio, have invented certain new and useful Improvements in Ironing-Machines, of which the following is a specification.

This invention relates generally to laundry machinery and particularly to yoke ironer operating mechanism for shirt presses.

More specifically this invention relates to suitable mechanism for shifting the yoke ironing member into place under great pressure to bring about perfect ironing of that portion of the shirt.

Referring to the drawings, Figure 1 is a front elevation of the machine; Fig. 2 is a side elevation; Fig. 3 is a top plan view of a portion of the machine; Fig. 4 is a detail rear elevation of the yoke ironer; and Fig. 5 is an enlarged detail view of the mechanism and associated parts.

In carrying out the invention any preferred form and construction of parts may be employed so long as they possess the necessary characteristics but I have shown one form in the drawings which is highly effective in operation and the several features will now be described.

A description of the particular machine in the embodiment shown in the drawings will now be given in a general way so that reference may be had to the several parts which form the subject matter of this invention. The machine comprises a suitable frame 1 having a forward support 2 and a rear support 3, the former having secured to it a stationary ironing member 3' which is of any suitable type but is preferably of the transversely curved shape, as shown in Fig. 1, with a yoke ironing member 4 as shown in Figs. 2 and 5. This yoke ironing member forms a part of the stationary ironing member and is curved as shown to give the proper shape to the yoke. Mounted on the rear support 3 is a pair of brackets 5 each provided with a suitable socket 6, these two sockets supporting the shaft member 7 forming a part of the movable ironing member 8. This ironing member is rocked upon this shaft toward and from the stationary ironing member in the usual manner.

Secured to the frame is a supporting guide plate 9 extending under the stationary ironing member 3' and under the yoke ironing member 4 and provided with suitable guideways 10 shown in Fig. 4, for guiding rollers 11 mounted on suitable shafts 12 carried by the yoke ironer 13 which is of a hollow construction so that heat may be applied thereto and is arranged to cooperate with the yoke ironing member forming a part of the stationary ironing member. This yoke ironer is provided with ears 14 upon its back and these ears are provided with a pin 15 engaging in a slot 16 in a rocking lever 17 pivoted upon a pin 18 in ears 19 forming a part of the guide plate 9. The lower end of this lever is provided with a slot 20 which receives a pin 21 carried by an arm 22 forming a part of a slide 23 engaging in a groove 24 in the underside of the guide plate 9 and held in place by suitable straps 25 secured to the underside of the guide plate in any suitable manner. The forward end of the slide 23 is provided with a pin 26 upon which is pivoted a link 27 in turn pivoted by means of a pin 28 to a rocker arm 29 keyed to a shaft 30 supported in suitable bearings in the frame and having keyed to its opposite end and to one side of the ironing member, as shown in Fig. 3, an operating arm 31 connected by a link 32 to a treadle 33 swiveled in suitable ears 34 forming a part of the frame. The arrangement of the foregoing parts is such that upon the depression of the treadle 33 the operating arm 31 rocks the rocker arm 29 in a counter clockwise direction, as shown in Fig. 2, to the position shown in Fig. 5, with the result that the toggle formed by the rocker arm 29 and the link is straightened causing the slide to be shifted to the left, as shown in Figs. 2 and 5, with the result that the lever 17 is rocked in a clockwise direction and the yoke ironer is forced with great pressure against the yoke upon the yoke ironing member. The pressure is sufficient to iron and press all parts of the yoke perfectly.

In order to release the yoke ironer, a treadle 35 is provided and it is swiveled in suitable ears 36 and is provided with a projection 37 projecting into the path of the lever 33, the arrangement being such that when the lever 33 is depressed the lever 35

is elevated, as shown in Fig. 5, so that the operator need only depress the lever 35 to release the yoke ironer.

Having described my invention, I claim: -

- 5 1. In an ironing press, a frame, bosom ironing members, a yoke ironer movable in a straight path toward and from one of said bosom ironing members, an operating member sliding in a path parallel to the path of movement of said yoke ironer, a double armed lever pivoted to the frame, pivotal connections between one of the arms of said lever and the yoke ironer and between the other arm of said lever and said operating member, said pivotal connections also having movement toward and from the pivotal connection of the lever to the frame as the yoke ironer travels back and forth in its path, and means for reciprocating said operating member.
- 10 2. In an ironing press, a frame, coöperating bosom ironing members, a yoke ironing member carried by one of said bosom iron-

ing members, a yoke ironer support mounted on the frame, a yoke ironer adapted to move along said support, a lever mounted in said support and having an arm provided with a slot for receiving a pin carried by the yoke ironer, another arm carried by said lever having a slot, a sliding bar mounted in said frame, a pin carried by said bar and engaging the slot in the second mentioned arm of the lever, treadle mechanism, a rock shaft mounted in the frame, an operating arm carried by said shaft, a link between said arm and the treadle mechanism, a toggle arm keyed to said rock shaft, and a toggle link connecting the toggle arm with the sliding bar.

In testimony whereof I affix my signature in presence of two witnesses.

LADBROOK H. FREEMAN.
